CLAIM

The ornamental design for a body attached tethered ball game goal, substantially as shown and described.

DESCRIPTION

FIG. 1 is a top view of a body attached tethered ball game goal, showing our new design;

FIG. 2 is a side or elevational view thereof;

FIG. 3 is a side view as viewed from the left of FIGS. 1 and 2, the opposite side of FIG. 3 being plain and unornamented; and,

FIG. 4 is a cross-sectional view of the basket portion taken along line IV—IV of FIG. 1.

Fig. 1.

Fig. 2.

Fig. 3.

Fig. 4.
